UNITED STATES PATENT OFFICE.

ABEL FERNANDEZ, OF WASHINGTON, DISTRICT OF COLUMBIA.

AUTOMATIC CUT-OUT SWITCH.

1,314,470.

Specification of Letters Patent. Patented Aug. 26, 1919.

Application filed March 2, 1918. Serial No. 220,085.

To all whom it may concern:

Be it known that I, ABEL FERNANDEZ, a citizen of Mexico, residing at Washington, in the District of Columbia, have invented 5 certain new and useful Improvements in Automatic Cut-Out Switches, of which the following is a specification.

This invention relates to improvements in automatic cut-outs or circuit closing devices 10 and it is the principal object of the invention to provide an automatic cut-out switch for use in connection with service lines whereby the overloading of the lines either 15 fraudulent or unintentionally will be positively prevented; the device serving to instantly break the circuit through the line should the same be overloaded at any time and to maintain the same open until manually closed.

20 Another and equally important object of the invention is to provide an automatic cut-out switch having means whereby the same can be opened or closed manually, irrespective of the automatic means, should it 25 be desired.

In order that the invention and the manner of its application may be readily understood by those skilled in the art, I have in the accompanying illustrative drawings and 30 in the detailed following description based thereon, set forth a preferred embodiment of the invention.

In the accompanying drawings:

Figure 1 is a top plan of the improved 35 cut-out,

Fig. 2 is a detail partly in section showing the means for securing the spring contact arms to the switch base,

Fig. 3 is a vertical transverse section there- 40 through,

Fig. 4 is a fragmentary longitudinal section through the handle,

Fig. 5 is a transverse section through the 45 slidable contact showing the mode of mount- ing,

Fig. 6 is a longitudinal section there- through,

Fig. 7 is a detail in perspective of the cam bearing element,

50 Fig. 8 is a fragmentary detail in perspective of one of the contact elements, and

Fig. 9 is a detail in section showing the adjusting connection for the thermal ele- 55 ment.

Having more particular reference to the

drawings, in connection with which like reference characters will designate corresponding parts throughout the several views, 1 represents the base of the improved switch, which as will be understood is formed of 60 porcelain or other insulating material and has spaced lugs or brackets 2 formed thereon, certain of which are apertured to permit the passing of an electrical conductor there- through, while ways 3 are formed in each 65 thereof and serve to retain elements herein- after described.

Circuit closing elements 4 and 5 are ar- ranged on the base 1 and as will be noted comprise arms formed of spring metal hav- 70 ing slots 6 formed therein adjacent certain of their ends, which ends are received in the ways formed in said lugs and securely held to the insulating base against displacement by engaging set screws 6' therein. By rea- 75 son of the apertures formed in certain of the spaced lugs, electrical conductors 7 and 7' may be passed therethrough into engage-

ment with the adjacent ends of said elements and connected thereto by a drop of solder or 80 similar conducting material. Mounted on the base in proximity to the outer or free end of the element 4 is a bracket 8 having its opposite end upturned and apertured whereby an insulated switch operating han- 85

dle 9 may be received therethrough said handle being formed of sections connected by the threaded bolt 9'. In this connection, it will be also noted that the adjacent end of the element 4 is apertured and is received 90 upon the arm 9 in order that it may be posi- tively engaged with the adjacent upturned end of the bracket 8. Other upturned por- 95

tions are formed upon one side of the bracket 8 and have a spring arm 10 secured thereto, which arm serves in the capacity of the latch means for the switch, by having the outer end of the same disposed to engage other circuit closing elements, hereinafter described, and to maintain the same in con- 100

tacting relation. Carried upon the intermediate portion of the arm is a hooked bracket 11 with which one end of a thermal ele- 105

ment 12 comprising a wire capable of ex- pansion and contraction when heated and cooled is engaged; the remaining end of said wire being secured to an arm 13 pro- vided with a screw threaded opening which receives an adjusting screw 14 thereon, said adjusting screw being mounted in suitable 110

bearings upon a bracket 15 secured to or formed integral with said base 1 in proximity to the opposite end thereof. Thus, it will be understood that the tension of the element 12 may be varied by adjusting the screw 14, such adjustment, obviously causing movement of the arm 13 to the proper position. Hence, should it be desired to regulate the thermal element 12 to cause the 10 release of the contact element immediately upon the overloading of the circuit, the screw 14 is adjusted to render the thermal element quite loose. Therefore, upon the heating of said thermal element, the same 15 will be permitted to quickly expand to its maximum and in this way release the contacts. To delay the breaking of the circuit, the screw 14 is then adjusted to render the thermal element taut and as a consequence 20 the same will be caused to expand to a greater extent before the contacts will be released. In this way, the thermal element can be easily adjusted to effect the release of the various contacts at predetermined 25 periods.

Other spring arms 16 and 17 are arranged on the base 1 in proximity to the opposite side thereof and as will be noted, are formed with projections, similar to the slots 6 in order 30 that the same may be permanently engaged between their respective spaced bosses. To limit movement of the free end of the arm 17, a stop 18 is arranged on said base and, obviously is adapted to be engaged 35 by said free end of the arm 17 under normal conditions. Arranged on the free portion of the arm 16 is a contact element 19, the same being insulated from said arm by means of a sleeve 20 formed of insulating 40 material. To the free end of the contact element 19, one end of a branch conductor 21 is secured, while the remaining end of said conductor is secured as at 22 to the bracket 13, and therefore has connection 45 with the thermal element 12. In this connection, attention is directed to the fact that the outer end of the arm 16 is arranged in proximity to the spring catch element 10. Carried upon the free portion of the arm 50 17 and insulated therefrom through the medium of a sleeve 23 is another contact element 24, this contact element, as will be noted, being bent forwardly in order that the same will be normally maintained in 55 spaced relation from the element or arm 17. By so forming the contact 24, a yieldable connection between the same and the contacts 19 is obtained, hence, insuring the closing of an electrical circuit. To the contact 60 24 one end of an electrical conductor 25 is secured, which conductor, as will be understood, forms a portion of one side of the circuit controlled by the switch.

A seat or way 26 is formed in the upper 65 face of the insulating base 1 and slidably

receives therein a contact element 27, one end of which is upturned as at 28 and is adapted to be engaged, at times, with the contact element 5. As means for normally maintaining the contact 27 in proper position with relation to the contact element 5, a coil spring 29 is arranged about the shank portion of the same and as will be understood, has suitable connection with a portion of said base. An electrical conductor 70 30 is connected to the contact 27 and of course, forms the remaining portion of the opposite side of the circuit in which the switch is interposed.

A cord or like connection 31 is arranged 80 on the base 1 and is passed over a suitable guide or pulley 35 secured thereto, one end of the same being engaged with the handle 9 as at 36, while the remaining end is engaged with a portion of the contact 27. 85 Arranged upon the base 1 at a point adjacent the shank of the handle 9 is a cam bearing element 37 which is adapted to be engaged by a laterally disposed finger 38 carried by said handle 9, which finger is 90 adapted to be arranged in a rabbeted portion or seat 37' formed on the upper marginal portion of said element 37, thus serving as means for holding the handle 9 in its adjusted position against rotation until 95 the same is released. Hence, when the handle 9 is rotated, the cord 31 will be coiled about the shank portion of the handle, while the finger 38 will cause said handle to move inwardly, thus effecting disengagement of the adjacent portion of the contact element 4 with the adjacent upturned end of the bracket 8.

To connect the elements 5 and 16, an insulated bolt 39 is provided and has its opposite ends passed through suitable openings formed in said elements and secured thereto by means of locking nuts 40 or similar fastening devices. In this way, complementary movement of said elements 5 105 and 16 will be caused.

In operation, to close the circuit through the conductors the handle 9 is pushed inwardly, thus engaging and moving the free end of the arm 16 inwardly whereupon the 115 contacts 19 and 24 will be engaged. At this time, the free end of the latch member 10 will snap under the free end of the element 16 and in consequence, maintain the contacts 19 and 24 in engagement. Simultaneously with movement of the element 16, the contact element 5 will be moved into engagement with the contact 27, thus completing the circuit; current passing from the conductor 7 through the element 4 and 120 bracket 8 into the thermal element 12 from the arm 10 from where it flows via the conductor 21 through the contacts 19 and 24 into the conductor 25 to the object receiving the same, the current returning through 125 130

the conductor 30, and the contact 27 to the arm 5 and thence, to the conductor 7' back to the source of energy. Assuming that the thermal element 12 is contracted, it of course will be understood that the latch member 10 will be maintained in engagement with the free end of the element 16 and as a consequence, the circuit will be held closed. However, should the line be overloaded either fraudulently or by short circuit, the thermal element 12 will become heated due to the excessive load and upon expansion will permit disengagement of the stop 10 from the free end of the element 16, whereupon said element 16 and element 5 will instantly move to their normal positions, thereby, opening or breaking the circuit through the electrical conductors. Should it be desired to break or open the circuit by the manually operated means, the handle 9 is rotated, thus causing the pulling of the contact 27, as well as the inward movement of said handle due to the provision of the cam bearing surface 37 and the finger 38. Such movement will of course cause the portion 28 of the contact 27 to move in a direction to cause disengagement of the same from from said element 5. Also, the back portion of the contact element 4 as engaged with the shank of the handle 9 will be moved out of engagement with the adjacent upturned portion of the bracket 8, thereby positively breaking the circuit through the conductors. The circuit may be again closed by pushing the handle 9 outwardly, thereby causing disengagement of the finger 38 from the rabbeted portion 37' and as a consequence, permitting free rotation of said handle and the return of the contact 27 to its normal engaging position. In this way, it will be appreciated that the cut-out may be operated irrespective of the automatic means comprising the thermal element 12.

Manifestly, the construction shown is capable of considerable modification and such modification as is within the scope of my claims, I consider within the spirit of my invention.

I claim:

1. In an automatic cut-out switch, a base, contact elements arranged on said base, other contact elements arranged on the base and engageable with said first contact elements, spring latch means for maintaining the second mentioned contact elements in engagement with said first contact elements, adjustable thermal means connected to said latching means for releasing the latching means and retaining the same in an adjusted position, a handle rotatably and slidably arranged on the base adapted to be engaged with one of said second mentioned contact elements, and means connected with said handle and one of the first mentioned

contact elements for causing disengagement of the same from said second mentioned contact element, at times.

2. In an automatic cut-out switch, a base, contact elements arranged on said base, other contact elements arranged on the base and engageable with said first contact elements, spring latch means for maintaining the second mentioned contact elements in engagement with said first contact elements, adjustable thermal means connected to said latching means for releasing the latching means and retaining the same in an adjusted position, a cam bearing element arranged adjacent one side of the base, a fixed contact arranged in proximity to said bearing element, a handle rotatably and slidably received on the base adjacent said cam bearing surface and fixed contact, a laterally extending finger carried by the handle engageable with the cam bearing element, a movable spring contact element normally engaged with said fixed contact element and connected to a portion of said handle and means connected with the handle and one of said first mentioned contact elements for causing disengagement of the same from its respective second mentioned contact, at times.

3. In an automatic cut-out switch, a base, independent contacts on said base, interconnected movable contact arms on the base insulated from each other and engageable with their respective contacts, latch means on the base engageable with one of said arms for releasably maintaining each of the arms in engagement with said contacts, a thermal element adjustably connected at one end to the base and connected at its other end to the latch means for normally maintaining said latch means in engagement with said contact arms, a cam bearing element arranged on the base, and a handle rotatably and slidably mounted on the base engageable with said cam bearing means for effecting initial engagement of the contact arms with their contacts.

4. In an automatic cut-out switch, a base, independent contacts on said base, one of the contacts being slidably engaged with the base, interconnected movable contact arms on the base insulated from each other and engageable with said contacts, spring latch means on the base engageable with one of said arms for releasably maintaining each of the arms in engagement with their respective contacts, a thermal element connected at one end to the base and at its other end to said latch means for normally maintaining the latch means in engagement with said contact arm, manual means for effecting initial engagement of the contact arms with their respective contacts, and means connecting the manual means to said slidably contacts for causing movement of

the same in a direction toward its respective contact arms upon operation of said manual means.

5. In an automatic cut-out switch, a base, 5 independent contacts on said base, one of the contacts being slidably engaged with the base, interconnected movable contact arms on the base insulated from each other and engageable with the contacts, a spring latch 10 arm secured to the base and engageable with one of said contact arms for releasably maintaining each of the arms in engagement with their respective contacts, a thermal element adjustably connected at one end 15 to the base and connected at its other end

to said spring latch arm for normally maintaining the latch arm in engagement with said contact arms, a cam bearing element on the base, an operating element rotatably and slidably mounted on the base engageable 20 with said cam bearing element, and means for connecting the operating element to said slideable contact for effecting movement of the same in a direction toward its respective contact arm upon rotation of the operating 25 element.

In testimony whereof, I affix my signature hereto.

ABEL FERNANDEZ.
